(57) CLAIM

The ornamental design for the scapular stabilizer, as shown and described.

DESCRIPTION

FIG. 1 is a rear elevational view of a first embodiment of a scapular stabilizer, showing my new design in use by an individual person depicted in phantom lines;

FIG. 2 is a front elevational view thereof, also showing the design in use by an individual person shown in phantom lines;

FIG. 3 is a perspective view thereof;

FIG. 4 is a right side elevational view thereof, the left side being a mirror image of the right side;

FIG. 5 is a top plan view thereof;

FIG. 6 is a bottom plan view thereof.

FIG. 7 is a rear elevational view of a second embodiment of a scapular stabilizer, showing my new design in use by an individual person depicted in phantom lines;

FIG. 8 is a front elevational view thereof, also showing the design in use by an individual person shown in phantom lines;

FIG. 9 is a perspective view thereof;

FIG. 10 is a right side elevational view thereof, the left side being a mirror image of the right side;

FIG. 11 is a top plan view thereof;

FIG. 12 is a bottom plan view thereof.

FIG. 13 is a rear elevational view of a third embodiment of a scapular stabilizer, showing my new design in use by an individual person depicted in phantom lines;

FIG. 14 is a front elevational view thereof, also showing the design in use by an individual person shown in phantom lines;

FIG. 15 is a perspective view thereof;

FIG. 16 is a right side elevational view thereof, the left side being a mirror image of the right side;

FIG. 17 is a top plan view thereof; and,

FIG. 18 is a bottom plan view thereof.

The broken lines showing a human figure illustrate environmental structure that forms no part of the claimed design.
